SHINGLE, SLATE, AND TILE ROOF

Filed April 20, 1925

INVENTOR:

Sherwood Badger Faison,

BY John Elie Jones,
ATTORNEY.

UNITED STATES PATENT OFFICE.

SHERWOOD BADGER FAISON, OF CINCINNATI, OHIO.

SHINGLE, SLATE, AND TILE ROOF.

Application filed April 20, 1925. Serial No. 24,612.

This invention relates to devices or means that are especially adapted for use in facilitating the accurate and speedy, as well as economical, laying of shingle, slate and tile roofs.

Heretofore, the laying off of a roof has had to be chalk-marked on the sheeting, or on the felt-cover of the sheeting of the roof-deck, a very tedious and rather unsatisfactory plan, requiring somewhat skilled and high-priced labor. The object, therefore, of my invention herein is to provide a layer of felt or similar cover for the sheeting comprising the roof-deck, such cover or layer being previously imprinted, stenciled, or otherwise marked with horizontal and vertical (or diagonal, if desired) lines that are duly arranged in the desired relation and intended for use as guide or pattern means whereby the workman, whether highly skilled or of limited experience, can instantly and accurately align and space (if desired) the shingles, slate, tile and the like that he is to use in making up the outer finishing-surface of the roof, thus economizing in time and in the degree or class of labor required, and being further adapted to various types of roofs, the said prior markings on the said felt layer or cover not being confined to any certain type but capable of a variety of forms and so arranged as to properly space and align shingles, slate, tile and the like of any size or outline, and suited to the deep lap of asphalt shingles and the tip or shallow lap of tile. Besides, the said imprinted felt-layer affords additional insulation to the roof and will help prevent leaks caused by driving rains, and more especially in connection with composition shingles somewhat needing such a lining or backing.

The details of structure and the method of laying the roof, to include my said felt imprinted or guide-marked layer, will be fully hereinafter described in connection with the accompanying sheet of drawings, in which—

Figure 1 is a plan view of one side of a roof that is made up of ordinary rectangular shingles, the latter being laid, according to my improved method or means and plan herein upon a previously or an already marked or guide-imprinted felt-layer for the roof-deck and adjacent to both slanting edges of a dormer-window, or other break or insert in the roof; and—

Figure 2 is a plan view similar to Figure 1, but showing my improved duly marked pattern or work sheets adapted to the use of diagonally-laid tile or shingles according to what is generally known and styled as the French method, wherein the upper angle or corner of the tile or shingle is placed at marked or specially determined intersections of horizontal and vertical lines as previously marked or charted on my said felt-layer.

I will first refer to the invention as illustrated in Figure 1. In this view, 3 indicates the felt layer or roof-sheeting cover that is laid in suitable widths, as usual, on the ordinary roof-deck composed of boards or sheeting A. On this felt-layer is imprinted or marked, in any suitable but accurate and approved manner, a series of continuous parallel horizontal lines 4 that are of uniform, equal distances apart to suit the depth of exposure of each shingle, slate, or tile and to upwardly space or block-off the roof, and I further imprint or mark on the said felt-layer a series of alternately staggered parallel vertical lines 5 that are of uniform equal distances apart to suit the width of the respective shingles, slates or tile and the intervals or spaces 6 to be allowed, as desired or as customary, in setting and securing said shingles, slates or tile in staggered array for use in making up a roof. Thus, the lines 4 serve for horizontal-spacing indicators or finder-guides, and the lines 5 serve for vertical-spacing indicators or finder-guides, in instantly and accurately setting or laying the respective shingles, slates or tile on the felt-layer or cover-sheet of the roof-deck for their subsequent nailing or fastening in permanent place, in due spaced or other desired alignment.

Nails 7 for the shingles, and nails 8 for the lapped edges 9 of the layer-felt widths, are provided to secure the said parts in place on the usual roof-deck.

10 indicates a dormer-window inserted in the roof and showing the manner of laying the rectangular shingles 11 in place adjacent both oblique edges 10^a, 10^b, thereof, a few courses, only, of shingles being shown, but sufficient, however, to illustrate the relation to the dormer-window of the already imprinted or marked felt-layer 3 that is made up of duly lapped lengths of predetermined or standardized widths and the adaptation of my invention herein to such circumstance.

I will now refer to the invention in the light illustrated in Figure 2, wherein square tile or shingles D are used instead of the elongated shingles 11 seen in Figure 1, and wherein, also, the guide-lines 4 and 12 intersect each other at right-angles, those 4 being the horizontal lines and those 12 being the vertical ones, the latter being continuous, instead of being staggered or alternating as in Figure 1. At alternating intersections, seen in said Figure 2, a cross or like device 13 is used by imprinting or otherwise marking it ahead on the felt-layer 3, to accurately and instantly determine and guide the workman in placing the tile or shingle D with its upper corner or apex (as it were) coincident therewith and with the sides of the tile or shingle at an angle of 45° to the said intersecting guide-lines 4 and 12. The shingles or tile D are properly trimmed for fitting in place against the sloping sides 10, 10^a of the dormer-window 10. Nails 8 are used to secure the lapped edges 9 of the lengths of the felt-layer 3 and nails C are likewise used in securing the shingles or tile D in place on the said felt-layer 3 and the roof-deck boards A beneath.

I claim:—

In a roof, the combination of a roof-deck, a plane unbroken sheeting-cover of felt or like material having previously imprinted on its upper surface suitably spaced and intersected guide-lines to form a pattern-chart whereby the laying and securing of shingles, slate, or tile outer-surface finishing-members is facilitated in a speedy and accurate manner to suit the various designs of roof to be effected, and fastening-nails driven through the said shingles, slate or tile finishing-members and the intervening pattern-chart into the said roof-deck, substantially as shown and described.

SHERWOOD BADGER FAISON.
